UNITED STATES PATENT OFFICE.

HENRY M. REICHENBACH, OF ROCHESTER, NEW YORK.

CARBURETER.

1,222,672.

Specification of Letters Patent.

Patented Apr. 17, 1917.

Application filed June 3, 1913, Serial No. 771,567. Renewed June 12, 1916. Serial No. 103,345.

To all whom it may concern:

Be it known that I, HENRY M. REICHENBACH, a citizen of the United States, residing at Rochester, in the county of Monroe and State of New York, have invented certain new and useful Improvements in Carbureters; and I do hereby declare the following to be a full, clear, and exact description of the invention, such as will enable others skilled in the art to which it appertains to make and use the same.

My invention relates to improvements in carbureters; and it consists in the constructions, combinations and arrangements herein described and claimed.

An object of my invention is to provide an improved carbureter adapted to produce an efficient mixture under all service conditions and to operate advantageously with either light or heavy fuel oils.

A further object of my invention is to provide a compact and strong carbureter which will operate with certainty and insure a high fuel economy.

In the accompanying drawings, forming a part of this application and in which similar reference symbols indicate corresponding parts in the several views:—

Figure 1 is a side elevation illustrating one embodiment of my invention;

Fig. 2 is a plan of the construction shown in Fig. 1;

Fig. 3 is a vertical section on the line 3—3 of Fig. 2;

Fig. 4 is an enlarged section on the line 4—4 of Fig. 2;

Fig. 5 is an enlarged horizontal section on the line 5—5 of Fig. 3;

Fig. 6 is an enlarged bottom end view of the telescoping sleeves for adjusting the fuel feed openings;

Fig. 7 is a section through Fig. 6; and

Fig. 8 is an enlarged end view of the slotted fuel-feed tubes.

Referring to the drawings, 1 indicates an open ended rectangular conduit adapted to be secured to the intake of an internal-combustion engine in any suitable manner, as by an end flange 2. A fuel tank 3 contains a preferably transparent or translucent float 4 provided with strong clips 5 adapted to lockingly engage any desired notch of which one is shown of a spaced series on the spindle 6 of an inlet valve 7, for adjusting the position of said float to vary the liquid level maintained thereby in said tank 3.

A series of fuel-supply tubes 11 extend from a fuel chamber 9 transversely within the rectangular conduit 1, which tubes are provided at their upper ends with rectangular slots 12, which preferably extend in a transverse plane of said conduit. Tubular sleeves 13 extend slidably through the upper wall of the conduit 1 and telescope snugly over the feed tubes 11; the upper ends of said sleeves being secured to a shiftable plate 14 and provided with air admission apertures 15. The lower ends of said sleeves 13 are provided with diametrical plates 16 constituting thin webs for fitting within the feed slots 12 to control said slots upon shifting of said sleeves 13; said shiftable plates 16 acting effectively to clean the feed slots 12 for preventing the troublesome clogging which has prevented the employment of efficiently narrow fuel feed slots in previous constructions. Cores 17 are secured concentrically on said webs to prevent the in-drawn current of air from depressing the fuel in the tubes 11.

By making the slots 12 rectangular in outline, I am enabled to establish easily a relation of differential proportioning between the effective opening of said slots and the effective divergence between the deflecting plates, by varying one dimension only. I cause the slots to become longer or shorter as the opening between the deflecting plates becomes wider or narrower. The rectangular shape of the conduit is of important consideration at this point, because this construction makes possible the use of rectangular straight edged plates as the sole controlling or constricting means for the effective air-opening or passageway. I am thus enabled to establish my differential curve in one plane, thus making the plotting of such curve and the corresponding construction of the curve of cam 19, a matter of comparative simplicity.

The tank 3 is shown clamped to the conduit 1 by a band 8 and connected to the fuel chamber 9 by a curved, or otherwise suitably shaped, pipe 10; said curved pipe providing a sufficiently yielding connection to permit shifting of the tank 3 to different positions within its clamping ring 8 for readily varying the level of the fuel in said tank to regulate the fuel level in the feed tubes 11.

As shown in the drawings, the inlet tank 3 is connected with a suitable source of fuel supply by an inlet pipe 18, which is formed

of flexible material, or otherwise constructed to permit adjustment of said tank within its clamping band 8.

A cam 19 is secured on a spindle 20 in position for actuating the shiftable plate 14 carrying the telescoping sleeves 13; said cam being formed to elevate the plate 14 with a progressively augmented action. As shown especially in Fig. 2, the spindle 20 is journaled in bearings on a slotted plate 21 adjustably secured on the conduit 1 by screws 22, for shifting said spindle to vary the position of the cam relative to the plate 14 and thereby govern the effectiveness of the fuel openings. A spring 32 engages the shiftable plate 14 for yieldingly maintaining the latter in contact with the cam 19; said spring tending to hold the telescoping sleeves 13 depressed to close the fuel feed slots 12.

The shape of this cam is made in accordance with the differential curve determined through trial, of the completely effective relation between the varying positions of the diverging deflectors or constricting plates and the width of the fuel feed slots determined by positions of the sleeves 13. Therefore, the position of the cam, which is determined by the position of the constricting throttle plates, which in turn is determined by the pull or suction of the engine, determines the differentially proportioned position of greatest efficiency, of the fuel supply controlling sleeves 13.

The spindle 20 is provided with a crank 23 having a series of perforations 24 for adjustable connection to a link 25 pivotally connected to a slide 26, on the conduit 1. The slide 26 is yieldingly maintained in its normal position by a spring 36, and is connected by links 27 to cranks 28 and 29 secured to shafts 30 and 31, respectively. A pair of rectangular deflectors 33 and 34 are secured on said shafts 30 and 31; said deflectors closely fitting within the rectangular conduit 1 and being yieldingly held with their free ends in contact by the spring 36 to normally close said conduit. As shown especially in Figs. 3 and 5, the free ends of the deflectors are bent, or offset, and provided with slots 35 for receiving the fuel tubes 11 and sleeves 13; said deflectors co-operating with the walls of the conduit 1 to provide a rectangular converging nozzle for directing the indrawn air in a jet directly across the rectangular feed slots 12 of said tubes 11. The rectangular conduit 1 is shown provided with a cylindrical intake end 37, in which is mounted a throttle valve 38 having a crank 39 for connection to any usual governor, or manually-operated mechanism. The nebulizing part of the carburetor is thus located between the throttle and the engine, so that by means of the throttle, the nebulizing elements may be

maintained in completely controlled relation to the engine suction, as well as kept during idleness from the contaminating dust of outside air as well as vapor losses.

In the operation of my invention, the deflectors 33 and 34 are swung apart by the engine suction to provide a rectangular conduit for directing the indrawn air in a jet directly across the rectangular fuel-feed slots 12; the actuation of said deflectors being proportionate to the degree of the engine suction, and the relation between the effective areas of the rectangular air-admission nozzle and the rectangular fuel-feed slots, being maintained under all service conditions.

By this construction, the indrawn jet of air acts effectively to draw in and to finely atomize or nebulize the fuel fed through the slots 12; thereby insuring an efficient and satisfactory mixture under all various operative conditions.

It is to be noted that the walls of the fuel feed openings are straight and perpendicular to the direction of the air current or feed blast. The blast is thus directly across the narrow slot or feed opening. Greater nebulizing efficiency is thus obtained. When the blast is along or parallel with a metallic surface, the liquid fuel is likely to creep along said surface, either with or against the blast. As it does so, it loses its more volatile constituents, and the heavier hydrocarbons left accumulate until they are taken off by the air current in the form of drops or blobs of considerable size. These drops when carried into the explosion cylinder, are oxidized only partially or not at all, and are carried by the exhaust into the atmosphere and wasted. I remedy this by leading a narrow effective blast straight across the straight walled narrow slots 12. It may be called a shearing blast, and all the paraffins or other hydrocarbons of the fuel are caught up at once and blown off in a nebula of finely atomized dry (i. e. free from drops) spray, and in a condition of maximum subdivision.

From the above description, it will be understood that my improved construction provides adjustable means for regulating the proportions of the air and fuel and the governing operation of the several parts; thereby adapting it for efficient use under all practical conditions and with both light and heavy fuel oils.

I have illustrated and described preferred and satisfactory constructions, but changes could be made within the spirit and scope of my invention.

I claim:—

1. In a carburetor, the combination of a rectangular inlet conduit for an internal combustion engine, a fuel-supply device provided with rectangular feed openings within

- 6 said conduit, a movable rectangular deflector within said conduit for directing the in-drawn air in a jet across such fuel-feed openings, and means controlled by said deflector for regulating such fuel-feed openings.
- 7 2. In a carbureter, the combination of an inlet conduit for an internal combustion engine, a fuel-supply device provided with feed openings within and extending across 10 said conduit, a suction-actuated movable deflector within said conduit for controlling the in-drawn air and directing the latter in a jet across such fuel-feed openings, and means controlled by said deflector for regulating 15 such fuel-feed openings.
- 8 3. In a carbureter, the combination of an inlet conduit for an internal combustion engine, a fuel-supply device provided with straight-edged feed openings, said device being so placed that the openings are made to extend across the conduit in such a position that the draft will be carried across the straight edges of said openings, a suction operated movable deflector within said conduit 20 for directing the in-drawn air in a jet across such fuel-feed openings, shiftable means for governing such fuel-feed openings, and connections between said deflector and shiftable means for actuating the latter.
- 9 4. In a carbureter, the combination of an inlet conduit for an internal combustion engine, a fuel-supply device provided with feed openings within and extending across 25 said conduit, substantially normally closed suction operated deflectors within said conduit for directing the in-drawn air in a jet across such fuel-feed openings, shiftable means for governing such fuel-feed openings, connections between said deflector and 30 shiftable means for actuating the fuel feed governing means, and means for normally maintaining said suction operated deflectors in closed position.
- 10 5. In a carbureter, the combination of an air inlet conduit for an internal combustion engine, suction operated means for permitting variable constriction of the effective opening in said conduit, a fuel-supply device provided with feed openings having 35 straight edges, said device being so arranged that the openings are made to extend across said conduit in such a position that the draft will be across the straight edges of said openings, and means for effecting differential 40 proportioning between said effective opening and said fuel feed openings in accordance with effective engine suction.
- 11 6. In a carbureter, the combination of an inlet conduit for internal combustion engines, suction operated means permitting constriction in one dimension of the effective opening of said conduit, a fuel-supply device provided with feed openings, said openings having straight edges and said device 45 being made to extend across said channel in such a position that the draft will be across the straight edges of the openings, and means for effecting differential proportioning between said feed openings and said effective conduit opening, in response to 50 effective engine suction.
- 12 7. In a carbureter, the combination of a fuel supply device provided with a rectangular feed opening, said opening being arranged in the intake so that the draft blows 55 across it, and means for varying the length of said opening in response to engine suction, in a ratio differentially proportioned between the feed opening and the air intake.
- 13 8. In a carbureter, the combination of a fuel-supply device provided with rectangular feed openings extending across the direction of the draft, in such a position that the draft will blow across the edges of said 60 rectangular openings, and automatic means for varying in one dimension only, the effective area of said openings in accordance with an established relation of differential proportion between said openings and intake of air, in accordance with engine suction.
- 14 9. In a fuel supplying and proportioning device having an air channel, the combination of a fuel-supply element provided with 65 an opening of elongated outline extending across the draft channel in such a position that the draft is carried across the long edges of said elongated opening, said fuel supply opening being controlled by planal 70 movement of a governing element, in accordance with a relation of differential proportion previously established between the effective dimension of such opening and intake of air, in accordance with engine suction.
- 15 10. In a carbureter, the combination of a fuel-supply device provided with feed slots, and means governing the linear dimension of such slots in accordance with a relation 75 of differential proportions previously established between the effective dimension of such slots and intake of air, said governing means being provided with an element engaging said slots for maintaining said slots 80 unobstructed.
- 16 11. In a carbureter, the combination of an inlet conduit for an internal combustion engine, a fuel-supply device provided with feed openings, said device being so positioned in the conduit that the draft is carried 85 across the edges of said openings, a movable deflector within said conduit for directing the in-drawn air in a jet across such fuel feed openings, means for normally maintaining 90 such fuel-feed openings closed, and means actuated by said deflector for opening such fuel-feed openings with a progressively augmented action.
- 17 12. In a carbureter, the combination of an 95

1. Inlet conduit for an internal combustion engine, a fuel-supply device provided with elongated feed openings within said conduit, said device being so positioned that the feed openings extend up and down in the conduit, a float tank supported on said conduit for supplying fuel at a constant level to said device, and means whereby said tank may be shifted to vary its level and consequently the level of supply to said feed openings.
2. In a carbureter, the combination of an inlet conduit for an internal combustion engine, a fuel-supply device provided with feed openings within and extending cross-wise said conduit, a movable inclined deflector co-operating with the walls of said conduit to provide a converging nozzle for directing the indrawn air at high velocity across such fuel-feed openings, and means controlled by said deflector for regulating such fuel-feed openings.
3. In a carbureter, the combination of a rectangular inlet conduit for an internal combustion engine, a fuel-supply device provided with rectangular feed openings within said conduit, a movable rectangular deflector inclined within said conduit and co-operating with the walls of the latter to provide a converging nozzle for directing the indrawn air at high velocity across such fuel-feed openings, and means controlled by said deflector for regulating such fuel-feed openings.
4. In a carbureter, the combination of an inlet conduit for an internal combustion engine, a fuel-supply device provided with feed openings within and extending cross-wise said conduit, a movable deflector inclined from one wall of said conduit to provide a converging nozzle for directing the indrawn air at high velocity across such fuel-feed openings, and means controlled by said deflector for regulating such fuel-feed openings.
5. In a carbureter, the combination of an inlet conduit for an internal combustion engine, a fuel supply, a pair of suction actuated deflectors converging within said conduit between the throttle and the engine for controlling the indrawn air, and connections between said deflectors for producing simultaneous equal movements thereof.
6. In a carbureter, the combination of an inlet conduit for an internal combustion engine, means for supplying fuel, a pair of suction-actuated deflectors converging within said conduit between the engine and the throttle to the air supplying means controlling the indrawn air, means for yieldingly maintaining said deflectors in contact for closing said conduit, and connections between said deflectors for producing simultaneous equal movements thereof.
7. In a carbureter, the combination of an inlet conduit between the throttle and the engine for an internal combustion engine, a fuel-supply device provided with feed openings within and extending across said conduit, a pair of suction-actuated deflectors converging within said conduit for directing the indrawn air in a jet across such fuel-feed openings, and connections between said deflectors for producing simultaneous equal movement thereof.
8. In a carbureter, the combination of an inlet conduit for an internal combustion engine, a fuel-supply device provided with feed openings within said conduit, a pair of suction-actuated deflectors converging within said conduit for directing the indrawn air in a jet across such fuel-feed openings, connections between said deflectors for producing simultaneous equal movement thereof, and means controlled by said deflectors for regulating such fuel-feed openings.
9. In a carbureter, the combination of an inlet conduit for an internal combustion engine, a fuel-supply device provided with feed openings within said conduit, a pair of suction-actuated deflectors converging within said conduit for directing the indrawn air in a jet across such fuel-feed openings, connections between said deflectors for producing simultaneous equal movement thereof, and means controlled by said deflectors for regulating such fuel-feed openings.
10. In a carbureter, the combination of a rectangular inlet conduit for an internal combustion engine, a fuel-supply device provided with rectangular feed openings within said conduit, a pair of suction-actuated rectangular deflectors converging within said conduit for directing the indrawn air in a jet across such fuel-feed openings, and shiftable means for regulating such fuel-feed openings, and connections between said deflectors and shiftable means for shifting the latter in fixed relation to the movement of said deflectors.
11. In a carbureter, the combination of an inlet conduit for an internal combustion engine, a fuel-supply device provided with feed openings within and extending across said conduit, a pair of suction-actuated deflectors converging within said conduit for directing the indrawn air in a jet across such fuel-feed openings, means for yieldingly maintaining said converging deflectors in contact to close said conduit, shiftable means for regulating such fuel-feed openings, means for normally maintaining said shiftable means closed, and connections between said deflectors and shiftable means for actuating the latter.
12. In a carbureter, the combination of an inlet conduit for an internal combustion engine, a fuel-supply device provided with feed openings within said conduit, a suction-actuated movable deflector within said conduit for directing the indrawn air in a jet across such fuel-feed openings, means controlled by said deflector for differentially controlling such fuel-feed openings, and a throttle valve in the intake end of said conduit.
13. In a carbureter, the combination of an inlet conduit for an internal combustion engine, a fuel-supply device provided with feed openings within said conduit, a pair of suction-actuated deflectors converging within said conduit for directing the indrawn air in a jet across such fuel-feed openings, and connections between said deflectors for producing simultaneous equal movements thereof.

within said conduit for directing the in-drawn air in a jet across such fuel-feed openings, connections between said deflectors for producing simultaneous equal movement thereof, and a throttle valve between the intake end of said conduit and said fuel-feed openings.

24. In a carbureter, the combination of an inlet conduit for an internal combustion engine, fuel-supply tubes provided with feed slots opening within said conduit, sleeves telescoping over said tubes, webs within said sleeves slidably fitting such feed slots, cores mounted on said webs concentrically within the telescoping portions of said tubes and sleeves, a suction-actuated deflector within said conduit for directing the in-drawn air in a jet across such fuel-feed slots, and connections between said deflector and telescoping sleeves for actuating the latter.

25. In a carbureter, the combination of an inlet conduit for an internal combustion engine, fuel-supply tubes provided with feed slots opening within said conduit, sleeves telescoping over said tubes, webs within said sleeves slidably fitting such feed slots, cores mounted on said webs concentrically within the telescoping portions of said tubes and sleeves, a suction-actuated deflector within said conduit for directing the in-drawn air in a jet across such fuel-feed slots, means for yieldingly maintaining said telescoping sleeves in closed positions, and connections between said deflector and telescoping sleeves for actuating the latter.

26. In a carbureter, an air conduit, a throttle valve for said conduit, a slotted fuel feed device, said device so positioned in the conduit that it discharges from its slot across the current, said device arranged between the throttle valve and the engine, said device discharging into said conduit, and suction-actuated means for controlling fuel supply in response to engine suction.

27. In a carbureter, an air conduit, a fuel feed device discharging into said conduit, said feed device provided with a slot extend-

ing crosswise said conduit, a cap arranged to cover said feed device and to vary the length of said slot in response to engine suction, said cap having an opening to the atmosphere to provide a safety suction vent.

28. In a carbureter, in combination, a rectangular conduit, a fuel supply device opening into said conduit, a spring-controlled deflector for directing air across said fuel opening, and means whereby proper relation between the effective area of the said fuel openings and that of the opening made by movement of the spring-controlled deflector is maintained constant.

29. In a carbureter, in combination, a conduit rectangular in cross section, a fuel feed device opening into said conduit, means for varying the size of said opening, and yieldingly controlled deflector plates converging toward the fuel opening for directing a blast across said fuel feed device opening.

30. In a carbureter for internal combustion engines, in combination, a conduit, a fuel supply device opening into said conduit, means for directing air past said fuel opening, means for varying the size of said opening, said means being connected to the air directing means, and additional means whereby air may be supplied to said fuel supply opening in a direction opposite to the direction in which the fuel flows.

31. In a carbureter, in combination, a conduit rectangular in cross section, a fuel feed device opening into said conduit, means for varying the size of the fuel opening, and yielding spring-controlled deflecting plates converging toward the fuel opening for directing a blast across said fuel feed device opening in proportion to the varying size of the opening.

In testimony whereof, I affix my signature, in presence of two witnesses.

HENRY M. REICHENBACH.
